N. SCHOLFIELD.

Bomb Lance.

No. 18,824.

Patented Dec. 8, 1857.

UNITED STATES PATENT OFFICE.

NATHAN SCHOLFIELD, OF NORWICH, CONNECTICUT.

CUSHION FOR WINGS OF BOMB-LANCES.

Specification forming part of Letters Patent No. 18,824, dated December 8, 1857.

To all whom it may concern:

Be it known that I, NATHAN SCHOLFIELD, of Norwich, New London county, and State of Connecticut, have invented a new and useful Improvement in Projectiles; and I do hereby declare that the following is a full and exact description thereof, reference being had to the accompanying drawings, making part of this specification.

My improvement consists in applying springs, cushions, or clasps, to neutralize the shock produced by a projectile on taking a case of guiding-wings from the muzzle of a gun in its discharge.

A A, Figure 1, is a sectional exhibit of a portion of the gun at the muzzle.

B is a surface view of a cylindric projectile just in the act of leaving the gun. The body of the projectile is turned a little smaller than the bore of the gun from which it is to be discharged, so as to allow a thin metallic case to intervene; but three ribs, *d*, extend longitudinally on the surface and at equal distances from each other, and of a thickness to accurately fit the bore. At the rear end is a collar, *C*, of a size to fill the bore, forward of which is a recess sufficient to allow of a spiral spring, *S*, or a ring or cushion of india-rubber or some compressible and elastic substance. A sliding collar, *G*, is also fitted loosely on this recess forward of the spring, and of a size to pass loosely into the gun.

e f g is a case made of three strips of thin metal in form of cylindric segments, soldered within the ring *f*. This is shown more perfectly and in perspective at Fig. 2. The outside of this case and the interior of the ring *f* should correspond in size with the greatest measure of the projectile, including the ribs, or with the bore of the gun, while the inner measure of the case should correspond with the diameter of the reduced part of the projectile, so that the case may be drawn on over the forward part by passing the strips of which it is formed between the ribs *d* until they come in contact with the sliding collar *G*; and the end of the case should be of a size to enter the muzzle of the gun, and should be placed therein, when used, so that the projectile may enter it accurately when discharged. Around this case is fitted loosely another cylindric case, *k l m*,

to which three guiding-wings, *W*, are attached. This latter case consists of a tube, *k m*, of a size sufficient to pass on over the former, having an enlargement or collar, *h*, at its rear end, or where it comes in contact with the collar *f* of the inner case. A ring or cushion, *i*, of some compressible and elastic substance, is placed between the collars.

The action of this projectile is as follows, viz: The body of the projectile, divested of the cases, which are both kept together as one, is inserted in the gun, observing carefully the positions of the ribs *d* as it enters. The case is then placed on over the muzzle of the gun, allowing the end *g* of the interior case to enter the bore, and in such positions in its circumference that the segments thereof shall come between the ribs *d* of the projectile as it passes out; and when discharged, and the collar *G* comes in contact with the end of the internal case, this is carried forward therewith, carrying with it also the outer case with the wings, the concussion thereon being modified through the intervention of the spring *S* between the two collars *C* and *G*, and of the elastic cushion *i*, and the whole passes off with the projectile.

Instead of a duplex case, these two cases may be connected together. The three segments of the inner case may be soldered or otherwise connected rigidly within the outer, or they may be connected thereto firmly only in the middle, allowing the ends *e* and *g* to spring inwardly, so as to clasp the projectile with some force as it passes in and through the case, by which means incipient motion is imparted to the case and wings before reaching the contact of the collar *G*.

If the projectile is of nearly the length of the gun the ribs *d*, as represented, may be dispensed with, and a single cylindric case carrying the wings will suffice; but in such case the tube must enter the bore of the gun sufficient to cover and sustain the anterior portion of the projectile to hold it steadily therein, and if the duplex case is used, the interior case at *g* must be produced downward sufficiently for that purpose; or if a single case with spring-clasps *e g* is used in the same connection, the end *g* of these clasps may be extended so as to reach into the gun sufficiently to clasp the anterior part of the projectile;

but in such case the rear end of the wings should extend downward without the gun as far as the end of the clasp within.

Instead of the cushion or collar *i* of india-rubber, a spiral or other spring may be used, and for this purpose the distance between the collars *f* and *h* may be increased, if necessary, and either one or the other of the springs *S* or *i* may be dispensed with, and if the spring *S* on the rear end of the projectile is omitted the collar *G* is also omitted, and the rear flange or collar, *C*, holds the case *e/f/g* in place; but if neither the spring *S* or *i* is used the case carrying the wings may be a single one, and may adjust itself in contact with the rear collar, *C*; and if the segments *e/g* within the case are elastic and curved inward, so as to clasp the projectile with force, incipient motion may be communicated thereby to the case, so that it would sustain the shock of striking the collar *C*; but without this clasp the concussion would be so violent as to destroy the case.

When these wings are fitted to a shell the rear recess, on which the spring *S* and sliding collar *G* is fitted, may consist of the fuse-chamber, which, for that purpose, is attached to the rear end of the body of the shell.

The ribs *d* on the body of the projectile and the segments *e/g* of the inner case should be so narrow as not to occupy the whole circumference thereof, in order to allow some variation in the angular position of the projectile compared with the case, and not bring the segments and ribs in contact when discharged.

It is found to be impracticable for a projectile to take the case of guiding-wings as it passes out of the gun without destroying or rendering them totally unfit for guiding it

without the use of springs, to prevent or modify the violent shock consequent on striking them instantaneously, for at the moment of leaving the gun the velocity is as great or greater than at any time afterward; and it will be readily acknowledged that if the case containing the wings should be placed at a distance therefrom and the projectile fired into it the shock would totally destroy it or render it unfit for use. This shock would be as great or greater at the muzzle of the gun; and to prevent this shock, resulting from putting the case in motion with the velocity of the projectile from a state of rest instantaneously, (as it must necessarily be if the case could thus acquire motion and remain unbroken,) I apply springs *S*, cushions *i*, and clasps *e/g*, and by their use (the three combined are best) the result is attained, and I am enabled thereby to so connect guiding-wings to a projectile as to serve a practical purpose. Therefore I do not claim the act of connecting guiding-wings or other apparatus to a projectile in its discharge.

What I claim as my invention, and for which I solicit Letters Patent, is—

The application of one or more springs, *S* or *i*, as a medium for modifying the effects of percussion of a projectile when entering a case of guiding-wings placed at the muzzle of a gun, to prevent the violent dynamical effect of a rigid and instantaneous concussion thereon by the projectile in its discharge.

NATHAN SCHOLFIELD.
